UNITED STATES PATENT OFFICE.

WOLDEMAR SCHUSTER, OF MARKNEUKIRCHEN, GERMANY.

CHIN-REST FOR VIOLINS.

SPECIFICATION forming part of Letters Patent No. 439,199, dated October 28, 1890.

Application filed October 3, 1889. Serial No. 325,836. (No model.) Patented in Germany January 22, 1889, No. 48,299.

To all whom it may concern:

Be it known that I, WOLDEMAR SCHUSTER, of Markneukirchen, in the Kingdom of Saxony, Germany, have invented an Improved

5 Chin-Rest for Violins and Similar Instruments, (for which I have obtained a patent in Germany, No. 48,299, dated January 22, 1889), of which the following is a specification.

This invention relates to a chin-rest for 10 violins, violas, and similar stringed musical instruments, which may be readily adjusted without detaching it from the instrument.

The invention consists in the various features of improvement more fully pointed out 15 in the claims.

In the accompanying drawings, Figure 1 is a face view of my improved chin-rest. Fig. 2 is a section on line Z Z, Fig. 1; Fig. 3, a top view thereof; Fig. 4, a section on line V V, Fig. 1; Fig. 5, a face view of a modification; Fig. 6, a top view thereof; Fig. 7, a face view of a further modification; Fig. 8, a section on line W W, Fig. 7; Fig. 9, a face view thereof, with the plate D inclined; Fig. 10, a face view 25 of the construction shown in Fig. 1, with the plate D inclined. Figs. 11 and 12 are face views of further modifications.

With particular reference to Figs. 1 to 4, the letter A represents the fixed jaw of the 30 chin-rest, from which project upwardly three screw-rods b a b. These screw-rods are embraced by the nuts f d f, in which enter the upper screw-rods b' a' b'. By turning the nuts these upper screw-rods are either raised 35 or lowered. To the central rod a' there is secured the movable jaw B, between which and the jaw A the violin is clamped. The upper ends of the rods b' are bent and enter laterally-extending slots or sockets in the chin- 40 plate D. These openings are preferably undercut for the reception of nuts m' on the ends of rods b'. To the jaw B there may be secured laterally-extending spring-arms e, that bear against the nuts f and prevent the 45 rest from being pulled backward by the chin.

In use the chin-rest is first clamped to the violin, and then the nuts f are turned until the rest is placed into the desired position. By turning one nut farther than the other 50 the plate D may be inclined, as shown in Fig. 10.

In Figs. 5 and 6 the screw-rods b b' are supplanted by a tube h, secured to jaw B, and by a rack g, secured to jaw A and entering said

tube. To the tube h there is secured a spring-pawl i, that engages the teeth of rack g. Thus the arms g h may be distended to any desired degree.

In Figs. 7 to 9 the rod b is supplanted by a socket b³, that receives a screw-rod f', secured to the nut f. To the upper part of this nut there is secured a socket f², that embraces the upper rod b'. By revolving the nut f the chin-rest is adjusted in like manner as in Fig. 1. If one nut is turned farther 65 than the other, any desirable inclination may be given to the plate D, as shown in Fig. 9.

In Fig. 11 the rod b is supplanted by a perforated tube b³, that receives a perforated bar b⁴, the latter taking the place of rod b'. A 70 pin b⁵, passing through the perforations of the parts b³ b⁴, serves to lock them at any desired position.

In Fig. 12 the rod a can be slid to the right or left on jaw A. In this way the chin-rest 75 may be shifted so as to project laterally over either side of the musical instrument.

In Figs. 10, 11, and 12 the laterally-extending sockets in plate D are replaced by the inwardly-bent upper ends of the rods that 80 engage said plate. Thus as one rod is raised farther than the other, the bent ends will turn in their seats, and in this way permit the plate D to be placed in an inclined direction.

I claim as my invention—

1. The combination of a fixed jaw with three upwardly-projecting extensible rods and with a movable jaw and a chin-plate, the central rod being connected to the movable jaw and the end rods being received by slots 90 in the chin-plate, so that the latter is free to be placed in an inclined position, substantially as specified.

2. The combination of jaw A with three upwardly-projecting extensible rods, a chin-plate D connected to the end rods, and a movable jaw B, connected to the central rod and having laterally-projecting spring-arms e, that bear against the end rods, substantially as specified.

In testimony whereof I have signed my name to this specification in the presence of two subscribing witnesses.

WOLDEMAR SCHUSTER.
